US0D1038740S

(12) **United States Design Patent** (10) **Patent No.:** **US D1,038,740 S**
(45) **Date of Patent:** **** Aug. 13, 2024**

(54) **D-RING WITH MULTIPLE OPENINGS**

(71) Applicants: **Buckingham Manufacturing Company, Inc.**, Binghamton, NY (US); **Jason Novak**, Goreville, IL (US)

(72) Inventors: **Kevin Truesdell**, Binghamton, NY (US); **DeForest Canfield**, Oxford, NY (US); **Jason Novak**, Goreville, IL (US)

(73) Assignee: **Buckingham Manufacturing Company, Inc.**, Binghamton, NY (US)

(**) Term: **15 Years**

(21) Appl. No.: **29/872,493**

(22) Filed: **Mar. 14, 2023**

Related U.S. Application Data

(63) Continuation of application No. 16/994,412, filed on Aug. 14, 2020, now Pat. No. 11,730,983.

(51) **LOC (14) Cl.** **08-11**

(52) **U.S. Cl.**

USPC **D8/367**

(57) **CLAIM**

The ornamental design for a D-ring with multiple openings design, as shown and described.

DESCRIPTION

FIG. 1 is a perspective view illustrating the D-ring with multiple openings design;

FIG. 2 is a top view thereof;

FIG. 3 is a bottom view thereof;

FIG. 4 is a front view thereof;

FIG. 5 is a back view thereof;

FIG. 6 is a side view thereof; and,

FIG. 7 is another side view thereof.

1 Claim, 7 Drawing Sheets
